A. Robeson
Cloth Finishing Mach.

N° 10,014.

Patented Sept. 13, 1853.

UNITED STATES PATENT OFFICE.

ANDREW ROBESON, JR., OF NEWPORT, RHODE ISLAND.

MODE OF BUCKING CLOTH.

Specification of Letters Patent No. 10,014, dated September 13, 1853.

To all whom it may concern:

Be it known that I, ANDREW ROBESON, Jr., of Newport, in the county of Newport and State of Rhode Island, have invented an Improved Mode of Bowking or Bucking Cloth; and I do hereby declare that the same is fully described and represented in the following specification and the accompanying drawings, letters, figures, and references thereof.

Of the said drawings Figure 1 exhibits a side elevation, Fig. 2 an end elevation, Fig. 3 a vertical, central, and transverse section, Fig. 4 a top view, and Fig. 5 a central and longitudinal section of the apparatus used in bowking cloth by my said invention.

In the said drawings A denotes a closed vessel or keir made of copper or other suitable material and divided into two chambers B, C, by means of a grating or perforated partition D.

E is a forcing pump whose induction pipe is seen at F as connected with an opening out of the lower part of the chamber C. 25 The eduction pipe of the said forcing pump is seen at G and as passing out of the top of the forcing pump on the upper valve chamber H thereof, through the side of the chamber C and up through the middle of 30 the chamber B and near the top of the same where it is surmounted by a meniscus shaped deflector.

K, L and M are the valves of the forcing pump, N its piston, and O its piston rod 35 which is worked up and down by means of an eccentric P fixed upon the shaft Q.

Into the upper part of the vessel A a steam pipe R is led, the said steam pipe being made to communicate with a steam 40 generator or boiler. The said steam pipe is provided with a safety valve S and a stop cock T. A small pipe U is also carried down through the middle of the vessel A from or near the top of the pipe G and 45 terminates at its bottom just below the grating D, and has a small safety or weighted valve V fixed upon its lower end.

In the use of the above described apparatus the goods to be bowked or bucked are 50 laid within the chamber B of the keir A and around the pipes G and U, the said chamber B being packed with the goods nearly up to the level of the top of the pipe U. The scouring or bowking liquor is 55 placed in the chamber C and such chamber is to be heated or not as occasion may re-

quire, by heat applied to its external surface.

The force pump being set in operation the hot liquor from the chamber C will be 60 drawn out of the lower part thereof and forced up through the pipe G against the deflector K by which it will be distributed upon the top surface of the cloth. Now if steam is let into the chamber B through the 65 pipe R it will press closely upon the cloth and bowking liquor thrown upon it, and will aid in causing a rapid filtration of the bowking liquor through the goods or cloth and into the chamber C. The bowking 70 liquor thus not only descends by the power of gravity as it does in the common process of using a keir, but it is forced downward and through the cloth by the superincumbent pressure of the steam. If the 75 pressure of the steam at any time exceeds the maximum pressure required for the operation of the keir, the safety valve V weighted to such maximum pressure will be forced open or raised and allow the steam 80 to escape into the chamber C where it will be condensed in the bowking liquor.

A pipe for the discharge of the contents of the vessel C may be led out of the bottom of the said vessel and be provided with 85 a stop cock and the vessel A may have an opening a through its top and a cover b to said opening as seen in the drawings, the said cover being provided with suitable contrivances by which it may be readily fixed 90 on or removed from the opening as occasion may require. The said opening a is intended for both the supplying of the goods and bowking liquor to the keir, or the removal of the goods therefrom.

I am aware that a keir has been constructed of two chambers, and that a lifting pump has been applied to the lower one to raise the working liquor from the lower chamber and discharge it into the upper one, 100 and in the top of the goods, the upper chamber being an open chamber, open at its top. Now the lower chamber being heated the steam arising from the bowking liquor in it is suffered to pass through a grating (dividing the two chambers) and upward through the goods or cloth. In this case the passage of the steam upward through the cloth, opposes and prevents to a considerable extent the infiltration of the bowking liquor. 105

I am also aware that a closed vessel or keir has been used and made with two apart-

ments divided by a grating essentially as represented in the accompanying drawings. Also that a pipe has been led from the middle of the grating and out of the lower 5 chamber and up through the upper chamber and provided with a deflector on its top. In this case heat being applied to the lower-most vessel, steam was made to ascend from the bowking liquor therein, and not only 10 pass up through the grating and goods, but through the pipe and upon top of the goods. In this last apparatus there being the same pressure of steam below the goods as there is above them, the filtration of the liquor 15 through the goods derives little or no assistance from the pressure of the steam.

I am also aware that an open keir has been made with two chambers and a central vomiting pipe covered by a deflector and that a 20 steam pipe has been led into the lower chamber to discharge steam into and heat the bowking liquor used therein. And that while the central pipe extended down some distance, the pressure of steam in the upper 25 part of said chamber would force the bowking liquor upward through the vomiting pipe and upon the top of the goods so that such liquor would descend through the goods and pass into the lower chamber of 30 the two chambers and through the grating which separated the two chambers. In this last instance the upward pressure of the steam against the lower part of the cloth or goods is opposed to the downward filtration 35 of the bowking liquor.

In my improved method of bowking the pressure of the steam is not only employed to saturate the goods, but to assist and increase the filtration of the bowking liquor 40 through them. The experiments I have performed have led me to discover, by the use of my apparatus, a very great saving of time and labor in the bowking of cloth. I am led to believe that there will be not only a saving of at least fifty per cent. in time, but 45 there will be great saving in fuel over the common process of bowking.

I am also aware, that a closed keir has been used in connection with a close vessel

placed by the side of it, and connected with 50 it and a steam generator and a cistern by such contrivances as would allow a liquid and steam to be alternately thrown into the upper part of the keir, the process of supplying the keir, with one being interrupted, 55 while that of the other was being carried on and the whole being for the purpose of separating and cleansing the fibers of hemp or certain other vegetable substances, in order to prepare them for being spun or 60 converted into yarns. This last differs essentially from my process of bowking, as by my said process, the keir is not supplied with the liquor and steam at different times, whereby the supplying it with the steam is 65 interrupted, while that of the liquor is going on, but both are carried on simultaneously under a constant pressure of the steam, the apparatus for the supply of the liquor being in constant operation. This makes a 70 very important improvement in the process, as the operation is a constant one, while the advantage of forcing the liquor down through the cloth by the pressure of the steam applied only on the top of the cloth 75 is maintained.

What therefore I claim as my invention or improvement is,

The employment of a closed keir or vessel as above described and extracting the bowking liquor from the lower part of it and forcing it into the upper part of it, while steam is being injected only into the upper part of the said vessel, and on the top of the goods whereby, while the bowking liquor is 85 being thrown on the top of the mass of goods, the steam is constantly and simultaneously made to press upon and pass into and through the goods, and facilitate the action of the bowking liquor and its passage 90 through the cloth as stated.

In testimony whereof I have hereto set my signature, this twenty-fourth day of September, A. D., 1852.

A. ROBESON, JR.
